OTTO FAHRNI, OF THOUNE, SWITZERLAND, ASSIGNOR TO LEOPOLD WYLER AND ANNA HELENA RIESER-BEUTTER, BOTH OF BERNE, SWITZERLAND.

MACHINE FOR PERFORATING JACQUARD-CARDS FOR EMBROIDERY-MACHINES.

1,379,807.

Specification of Letters Patent. Patented May 31, 1921.

Application filed November 8, 1920. Serial No. 422,655.

To all whom it may concern:

Be it known that I, OTTO FAHRNI, a citizen of the Swiss Confederation, and residing at Thoune, Switzerland, have invented 5 certain new and useful Improvements in Machines for Perforating Jacquard-Cards for Embroidery-Machines, of which the following is a specification.

This invention relates to machines for 10 perforating jacquard cards for embroidery machines of the kind wherein a controlling device comprising a main determinative member having means arranged in rows is provided for controlling the punching de- 15 vice for each component of movement of the embroidering frame, and wherein an auxiliary determinative member actuated by a member rotating with the said main determinative member is provided for indicating 20 the direction of movement of the same beyond its zero position.

Machines of this kind known heretofore had the defect that when the main determinative or control member, such as a cylinder 25 having perforations of pins, moved beyond its initial position the operator had suddenly to employ more force in order to overcome the resistance opposing the operation of the pattern-copying apparatus, be- 30 cause then the auxiliary determinative or control member, such as a segment or key, had to be brought directly into a new position, the consequence of which always was that owing to the inertia of the moving 35 masses at the usual working speed, the stitch to be made was always too large if one or both of its ends required an adjustment of the main control member to a position near its initial or zero position.

40 A primary object of this invention is to obviate this defect.

To this end, in the machine described hereinafter the movements of the main control member are imparted continuously to 45 the auxiliary control member by means of a positive clutch and positive backward transmission, means being provided for causing movements of the same that do not pass beyond the zero position of the main control 50 member to be inoperative on the auxiliary control member for the punching operation, and to return the auxiliary control member into the zero position after the same.

To these and other ends, the invention

consists in the construction, arrangement 55 and combination of parts described herein-after and pointed out in the claims.

One embodiment of the invention is illus- 60 trated by way of example in the accompany- ing drawing, wherein:

Figure 1 is a longitudinal elevation partly in vertical section taken on the bent line I—I in Fig. 2 showing one form of ma- 65 chine according to the invention,

Fig. 2 is a top plan view thereof, some 65 parts in the lower half of the figure having been removed, and

Figs. 3 and 4 are detail views.

Fig. 5 is a detail in section, illustrating a worm - wheel and a three-armed lever 70 clutched thereto; and

Fig. 6 is a detail illustrating the spiral thread formed on one of the perforated cylinders.

Like reference numerals designate like 75 parts throughout the several views.

Referring to the drawing, the main frame of the machine comprises two longitudinal side frames 1 and 2 which are connected at their one end by a cross frame 3 and carry 80 at their other end a horizontal driving shaft 4. A driving pulley 5 is loose on the end of this shaft that projects beyond the frame 1. The hub 6 of this wheel constitutes a crown wheel having ratchet teeth on its inner end face, with which a similarly formed clutch member 7 of an arresting disk 8 that is axially slidable along the shaft 4 can be engaged when the disk 8 is shifted by the operator toward the pulley 5 against 90 the action of a spring 11 situated between these disks by means of an angle lever 9 and a sliding ring 10 connected therewith. The pulley 5 can thereby be clutched with the shaft 4 so that it will rotate the latter 95 in the direction of the arrow shown in Fig. 1.

The disk 8 has a flange 12 that projects laterally toward the frame 1, and has cut in it a recess 13 that slopes inward gradu- 100 ally on the one side and outward steeply on the other side. When the disk is in its engaged position its flange slidingly coacts with an antifriction roller 14 fixedly mounted on the frame 1. Owing to the action of 105 the spring 11 the disk 8 is pushed away from and disengaged from the pulley 5 whenever the roller 14 enters into the recess 13. As

soon as the roller 14 is at the bottom of this recess, the disk 8 is arrested and with it the shaft 4. Consequently, the claw clutch 6, 7 is disengaged once every revolution and 5 always stops the shaft 4 in the same position.

Cams 15 and 16 and two cams 17 and 18 are fast on the shaft 4 between the two side frames 1 and 2. The anti-friction roller 10 19 of a lever 20, 21, 22 coacts with the periphery of the cam 15. The downwardly projecting arms 21 and 22 are connected respectively to the one end of two rods 23 and 24 of adjustable length, the other ends 15 of which are pivotally connected to angle levers 25 and 26, respectively. Each of the same is provided at the free end of its upper arm with a tooth that slopes on both sides, by means of which a toothed wheel 27 arranged at the side frames 1, 2 above the angle levers 25 and 26 and having tooth-gaps or teeth corresponding with the shape of the said tooth can be placed and arrested exactly in positions corresponding to pitch 20 of the same.

The toothed wheels 27 are respectively fast on sleeves 29, whereof only one is shown, free to rotate about the fixed spindle 31 common to the two. The two wheels 27 30 have each on its inner end face a pinion 32, and 33 respectively, of which the former meshes with a gear wheel 34 and the other with a gear wheel 35. The wheel 34 is fast on a shaft 36, on which a sleeve 37 carrying 35 the wheel 35 is free to rotate; this sleeve 37 has outside the frame 2 a pinion 38, beside which is a pinion 39 fast on the shaft 36.

The pinions 38 and 39 are positively connected with a well-known adjusting apparatus, not shown, to be actuated according 40 to a pattern drawing, whereof the pinion 38 for example brings about the adjustments for the horizontal feed, and the pinion 39 the adjustments for the vertical feed of a 45 frame of an embroidering machine. The pinion 38 imparts its rotation to the sleeve 37, and the wheel 35 to the one sleeve on the spindle 31, whereas the pinion 39 acts by means of the shaft 36, and the gear wheels 34 and 32 on the other sleeve 29 on the spindle 31.

The sleeves 29 which, as will be understood from the above, are rotatable independently one of the other, carry fast on 55 them each a perforated cylinder 40, 41, herein referred to as main determinative members, between each of these and the allotted pinion 32 or 33 an arm 42 having laterally projecting driving pins 43, further 60 an axially slid able worm 44 and 45 respectively driven by these latter pins, and lastly each a segment 46, and 47 respectively, herein referred to as auxiliary determinative members, each rotatable between the 65 two perforated cylinders 40 and 41.

Corresponding to the number of teeth of the wheels 27 the cylinders 40 are provided each with sixty axially disposed rows of perforations which, commencing with six as the largest number in the zero position, 70 is each a different combination of holes. Of these sixty combinations each serves for determining a predetermined amount of movement of an embroidering-machine controlled by jaquard cards, the perforated cylinder in question being turned or moved a predetermined amount. For example, if a movement of one complete revolution of one of the perforated cylinders corresponds to a displacement of the frame (movement 80 component) of 5 mm. as a unit, a movement of the perforated cylinder from one row of holes to the next will correspond to a frame displacement of 1/12 mm., and a movement of two rows to a frame displacement of 2/12 mm., and so on up to 60/12 mm. units.

When the perforated cylinders are situated in the zero position the rows of holes corresponding to zero are situated in the 90 horizontal axial plane of the cylinders opposite the reduced ends of six horizontal, axially slidable feeler pins 50 guided in two cross-bars 48 and 49. The other ends of the pins 50 are formed as flat sinkers constituting bolts which project close together between two flat bars 52 placed one above the other and provided with as many vertical holes 53 as there are sinkers extending between them. Into the holes 53 of the lower 100 bar 52 there extend from below the upper ends of vertical punches 54, whereof the lower ends extend through a flat bar 55 into a bar 56 below the same and normally rest by means of a collar 57 on the bar 55. 105 Between this bar 56 and a similar bar 60 below the same is a small gap 59 for guiding a card band 58.

These bars 56 and 60 are supported on a beam 62 that has a vertical longitudinal slot 110 61 and is suspended at its ends from two vertical rods 63. These rods are guided to move longitudinally in a cross beam 64 that carries the bars 52 and 55, and are pivoted at their upper ends each to the forked end 115 of a lever 65. Between these levers 65 the shaft 66 on which both are fulcrumed carries a lever 67, the free end of which coacts by means of an anti-friction roller 68 with the cam groove 69 of the disk 16, by which 120 at each revolution of the same a rapid vertical reciprocating movement is imparted to the levers 67, 65, the rods 63, the cross-beam 62 and the bars 60 and 56. The band 58 is thus also reciprocated vertically. 125

If the path of the punches 54 is free, that is to say, if none of the sinkers 51 covers one of the holes 53 of the lower bar 52, then all the punches are lifted by the band, they can move freely vertically and there- 130

fore make no holes in the band. This is the case when some of the feeler pins 50 can enter into holes in the cylinder 40 and 41 on their being moved toward them in the manner described hereinafter. If there is no hole in the cylinder opposite one or another of the pins 50, on the contrary, then its sinker covers over the allotted hole 53 in the lower bar 52, thus blocks the path of 5 the punch 54 and prevents its lifting when the band 58 moves upward. Consequently, a hole is punched in the band for the feeler pin of the embroidering automatic gear. The pieces punched out of the band fall 10 through the slot 61 of the cross-beam 62 into a drawer 70 supported below the latter on the frames 1 and 2.

As long as the perforated cylinders turn between two zero positions, that is within 15 the same unit, for example between 1/12 and 59/12 units, no device is required for indicating the direction of rotation of the cylinders or the direction of the stitch, since it follows at once from two adjacent combinations of perforations. If the zero position is passed in the one or other direction, however, the card for each perforated cylinder must have a particular perforation which shall release in the embroidering pattern gear those members which are responsible for maintaining the correct direction of movement of the embroidering frame beyond the limit of one unit, in order that when a cylinder has moved, for example, 25 from 1/12 units in a negative sense to 58/12 units, the pattern gear shall not feed the embroidering frame in the positive sense from 1/12 units to 58/12 units. For this purpose the device that will now be described is provided.

Each of the cylinders 40 is provided on its outer end with a spiral thread 71, whereof the beginning and end coincide with the zero position or perforation of the cylinder 30 and together form a step or shoulder 72. To these threads 71 is allotted each a feeler pin 73 which differs from the feeler pins 50 in being of somewhat larger diameter; also in its retracted position it projects beyond the latter. In Figs. 1 and 2 only one 35 of these feeler pins 73 is visible. They are pivoted at their rear ends each to a two-armed lever 74, from which a link 75 leads to a bell-crank lever 76 that is fulcrumed on a vertical pivot and engages by means of a sliding segment 77 in an annular groove 78 formed in the hub of its allotted worm 44. The worm wheels 79 and 80, meshing therewith are each rotatably mounted on a 40 sleeve 81 which, in turn, is mounted on an eccentric pivot formed on an axial 83 adjustably secured in the cross-bar 3. The sleeve 81 carries at one end a three-armed lever 84 (Figs. 1, 2 and 3), and at its other 45 end a lever 85 that is connected by means

of a link 86 and two members 87 and 88 at right angles to one another with the forwardly (toward the left hand) projecting arm 89 of its allotted segment 46. A spring 90 bearing against the lever 85 presses the 45 worm wheel 79 or 80 against the lever 84, whose upwardly projecting arm carries a pin in the form of a screw 91 having at its end facing the worm wheel a point with which it engages in recesses or notches provided in that face of the wheel and thereby clutches the worm wheel with the lever 84, the arrangement being such that so far as the axial play of the allotted worm admits thereof, the worm wheel drives the pin, or 50 vice versa, according as the worm or lever 84 is turned, while the clutch is disengaged, however, by forcing the worm wheel axially against the action of the spring 90 when the lever 84 is turned further or indeed is turned 55 in that direction in which the worm prevents rotation of the worm wheel in mesh with it.

In consequence of this device, hereinafter referred to as a compensation device, when 50 the perforated cylinders 40 and 41 are rotated the segments 46 and 47 are likewise rotated, but with a considerably reduced velocity owing to the reduction gearing, so that for each revolution of the perforated 55 cylinders the segments are rotated only a fraction of a revolution, but in the same direction, as is the case for example in counting mechanism, in which the counting member for the units acts on the counting member for the tens. For marking the zero position, each of the segments 46 and 47 has in the middle of its arc three holes, into each of which a feeler pin 93 enters when the segments occupy a central position. The 60 feeler pins 93 control each a punch 54, analogously to the pins 50, with the aid of bolt sinkers, so that no holes are made in the band when the allotted feeler pins 93 can enter into holes in the segments. Consequently, it follows that holes are punched in the band when, as in the case of the pins coacting with the perforated cylinders, the 65 feeler pins 93 strike against the segments.

As this, in the case of the perforated cylinders, constitutes means for indicating the amount of displacement of the embroidering frame, so here this means can be used firstly for indicating the direction of motion of the 70 embroidering frame for the stitch to be made beyond the unit of length and, secondly, for indicating the amount of such excess in the case of each single stitch.

For the first of these indications, the segment 46 has in the middle of its breadth in 75 its upper half, and likewise the segment 47 has in the middle of its breadth, but in its lower half, a vertical row of perforations (Fig. 3), so that the middle feeler pin of the segment 46 can not enter into a 80

hole in the same when this segment moves upward. The reverse is the case with the middle feeler pin of the segment 47, for it can enter into a hole in the 5 same only when the segment has moved upward. From the combination of a hole in the pattern band due to a middle feeler of the segment 46 or 47 with a transverse row due to the allotted perforated cylinder there 10 can consequently be ascertained the direction of the one component of movement of the embroidering frame beyond the unit length. How frequently this unit limit or initial position is exceeded in a stitch to be 15 made is seen from the combination of two other rows of holes of the same segment with a transverse row due to the allotted perforated cylinder; for example, if the zero position of a perforated cylinder is exceeded 20 once the allotted segment moves out of the zero position one division of the cross rows whether the cylinder in question make a complete or only part of a revolution. If it makes one complete revolution then the correct adjustment of 25 the segment results automatically from the positive arrangement of the transmission; if it is only part of a revolution the described compensation device comes 30 into operation, the allotted feeler pin 73 bearing on a more or less deep part of its spiral thread 71 corresponding to the amount of angular movement of the perforated cylinder and therefore experiencing 35 a greater or less longitudinal displacement which is imparted by the lever mechanism 74, 75, 76 to the worm which, in turn, is thereby shifted axially more or less and turns the worm wheel forward still further 40 than it would be turned by one complete revolution of the worm in question. This additional angular movement of the worm wheel is imparted by the parts 91, 84, 85, 87, 86, 88 and 89 to the segment 46 or 47 45 which is thereby so adjusted as if the allotted perforated cylinder had turned one complete revolution, in order that the feeler pins 93 shall actually register exactly with a hole of the segments when one is provided. 50 This play of the compensation device just described above occurs also when the zero position of a perforated cylinder that is shifted is not passed, only in this case the compensation device acts always in a negative, that is a backward sense on the segment, in order that in spite of the positive connection between perforated cylinder and segment, the latter shall always occupy the zero position when the feeler pins are moved 55 60 forward. After each withdrawal of the feeler pins out of the perforated cylinders and segments, the segments whether shifted in one direction or the other are returned into the middle or zero position; this is done 65 by a lever 95, that carries a semicircular

yoke 94, acting by means of this yoke from below on the downwardly slanting arm of the lever 84 that is shifted out of its middle position until this lever again occupies the middle position, wherein both the laterally 70 projecting arms of the lever 84 contact with the ends of the yoke 94 when the lever 95 occupies its upper end position. The two levers 95 mounted on a sleeve 100 free to rotate on a shaft 99 are actuated by the cam 17 75 through the medium of lever mechanism 96, 97, 98. The feeler pins are advanced toward the perforated cylinders and segments by springs 101 that surround the pins between the two 80 cross bars 48 and 49; these springs bear at one end against the cross bar 48 and at the other end against pins 102 that extend upwardly from the feeler pins and simultaneously serve for withdrawing the feeler 85 pins from the front into the rear end position with the aid of a beam 103 that is disposed transversely over them and is guided in horizontal longitudinal slots in the frames 1 and 2. The beam 103 is reciprocated by two levers 105 and 106 that engage 90 pivots 104 on its ends and are both fast on a shaft 107, the lever 106 being connected by a link 108 with a lever 109 coacting with the cam 18. 95

The card band 58 is fed intermittently by the pair of rollers 110, 111, whereof the lower one, 110, has on its periphery two rows of sprockets 112 that take into holes punched in the band. For obtaining the requisite 100 space between these holes the punches 54' for punching the same operate at only every second punching operation. For this purpose the path of the two punches that are used is blocked by means of bolt sinkers 117 at 105 every alternate movement of the roller 110 which is intermittently rotated by means of a ratchet wheel 113 fast on its axle, a pawl 114, (Figs. 2 and 4) that engages with this wheel, a lever 115 pivotally connected with 110 the pawl and a cam 116 that is fast on the driving shaft 4 and actuates this lever 115. The sinkers 117 are pivoted to levers 118 mounted on a shaft 119 that carries outside the frame 2 a two-armed pawl 120 (Figs. 2 115 and 4.) This pawl is pressed by a spring 121 against the periphery of a notched disk 122 mounted on the ratchet wheel 113; the ratio of the number of notches in the disk 122 to the number of teeth of the ratchet 120 wheel 113 is 1:2, so that every alternate movement of the ratchet wheel the pawl 120 bears on the top of a tooth of the notched disk 122 and holds the shaft 119 in such a position that the sinkers 117 block the path 125 of the punches associated with them, whereas when the pawl 120 takes into a notch in the disk 120 they no longer obstruct the path of the said punches, so that the latter produce no holes in the card band at the 130

following punching operation. The adjustment of the feed roller 110 into the correct position at any time, and its arrest in the same, is automatically effected by means of a 5 toothed wheel 123 that is mounted on the axle of the feed roller and has teeth slanting on both sides, between which engages a spring-controlled pawl 124.

For making holes in the pattern band for 10 the special functions of an embroidering machine to be controlled by the same there are arranged besides the two feeler pins 73, two sets of six feeler pins 125 which, like the pins 50, control each a punch by means of 15 a bolt sinker and are controlled by a design plate 127 that is common to a set of six and is reciprocated vertically in vertical guides 126 by the operator manually, or automatically by mechanism not shown in the 20 drawing.

The hereinafter described mode of operation of the described machine relates to only one of the perforated cylinders and its allotted segment and to one revolution of the 25 driving shaft 4.

In the inoperative position of the machine the clutch 6, 7 is disengaged, the driving shaft 4 is arrested by the disks 8, 12 and the roller 14, all the feeler pins are in their rear 30 end position, the segments 46 and 47 are situated each in its zero position, each toothed wheel 27 is released by its pawl 25 or 26 and the perforated cylinders 40 are thereby also released so that they can be 35 adjusted at will.

The perforated cylinder 40, for example, is set by turning the pinion 39. If the adjustment has taken place, for example, to 40 58/12 units from the zero position in a positive direction, the perforated cylinder will not have made a complete revolution and the segment 46 will have been shifted downward from its middle position not quite one division between the holes, when the perforated cylinder in Fig. 1 has been moved 45 clockwise. After the setting of the perforated cylinder the arresting disks 8, 12 are shifted against the action of the spring 11 by actuating the lever 9 and the clutch 6, 7 50 is thereby engaged.

When the shaft 4 is rotated counter clockwise as seen in Fig. 1 the pawl 25 is first engaged with the toothed wheel 27 and the perforated cylinder is thereby so set and 55 arrested that the desired row of holes is situated exactly opposite the feeler pins 50, should this not be the case already. The beam 103 is then moved toward the perforated cylinder. At the same time the feeler 60 pins also shift forward, whereof the pin 73 first contacts with the spiral thread 71, the feeler pins 125 for the holes of the special functions then or simultaneously contact with the design plate 127, and lastly 65 the feeler pins or design pins 50 or respec-

tively 93, contact with the perforated cylinder 40 and the segment 46, respectively, the segment having in the meantime been returned by the compensation device into the zero position, because the zero or initial 70 position of the perforated cylinder was not passed when setting the same.

All the feeler pins 93 allotted to the segment 46 enter each into a hole therein, and for example the five lower design pins 50 in 75 Fig. 2 enter into the perforated cylinder. Consequently, only the top design pin 50 enters into a hole of the perforated cylinder, while the five others butt against the cylinder, block with their bolt sinkers 51 80 the path of the allotted punches which punch each a hole in the card band 58 during its upward movement which now takes place.

Immediately after this punching operation the card band is moved downward and fed one step forward and the feed roller 110 is arrested by the pawl mechanism 123, 124. All the feeler pins moved somewhat away 85 from the perforated cylinder or segment are 90 thereupon withdrawn by means of the cross beam 103.

If the perforated cylinder during its previous adjustment had been moved beyond the initial or zero position and the segment 95 had been set one or more divisions away from its middle position, the replacement of the segment would be included in the described sequence of operations, this being effected by the yoke of the lever 95. Then 100 the feeler pins are completely withdrawn and lastly the arresting members 25 and 27 of the perforated cylinder and the driving clutch of the shaft 4 are disengaged, and the shaft 4 is secured against unintentional 105 rotation by the disks 8, 12 and the roller 14.

The perforated cylinder can now be set afresh, and the described cycle of operations can be repeated.

I claim:

1. In a machine of the character described for perforating jacquard cards for embroidering machines, the combination with a punching device comprising a plurality of feeler members, a rotatable main determinative member arranged to control some of said feelers selectively and an auxiliary determinative member arranged to selectively control other of said feelers, of means positively connecting the said main and auxiliary determinative members together and arranged to impart the rotary movement of the former to the latter, said auxiliary determinative member being so arranged that the feelers controlled thereby are inoperative on the punching device when the main determinative member does not pass its zero position, and means for returning the said auxiliary determinative member into its zero position 110 115 120 125 130

independently of the movement of said main determinative member, substantially as set forth.

2. In a machine of the character described for perforating jacquard cards for embroidering machines, the combination with a punching device comprising a plurality of feeler members, a rotatable main determinative member arranged to selectively control some of said feeler members, and a rotatory auxiliary determinative member arranged to selectively control other of said feelers and so constituted that the feelers controlled thereby are inoperative on the punching device when the main determinative member does not pass its zero position, of a transmission member rotatable with, but slidable axially relatively to said main determinative member, means positively connecting said transmission member with said auxiliary determinative member and arranged to transmit both the said axial and rotatory movement of the said transmission member to said auxiliary determinative member, and means for returning the said auxiliary determinative member into its zero position independently of the movement of said main determinative member, substantially as set forth.
3. In a machine of the character described for perforating jacquard cards for embroidering machines, the combination with a punching device comprising a plurality of feeler members, a rotatable perforated cylinder arranged to selectively control some of said feeler members, and a rotatory perforated segment arranged to selectively control other of said feeler members and so constituted that the feeler members controlled thereby are inoperative on the punching device when said cylinder does not rotate beyond its zero position, of a worm rotatable with, but slidable axially relatively to said cylinder, means comprising a clutch positively connecting said worm with said segment and arranged to transmit both axial and rotatory movements of said worm to said segment, means controlled by said cylinder for moving said worm axially according to the amount of angular movement imparted to said cylinder from its zero position, and means for returning said segment into its zero position independently of the movement of said cylinder, substantially as set forth.

4. In a machine of the character described for perforating jacquard cards for embroidering machines, the combination of a punching device comprising a plurality of feeler members, a rotatable perforated cylinder arranged to selectively control some of said feeler members, and having a spiral thread on its periphery whereof the beginning and end are in line with the zero perforations of the cylinder, a rotatory perforated seg-

ment arranged to selectively control other of said feeler members and so constituted that the feeler members controlled thereby are inoperative on the punching device when the said cylinder does not rotate beyond its zero position, a feeler member arranged to coact with said spiral thread, a worm rotatable with, but slidable axially relatively to said cylinder, means comprising a clutch arranged to transmit both axial and rotatory movements of said worm to said segment, means comprising a feeler member arranged to coact with said spiral thread for moving said worm axially according to the amount of angular movement imparted to said cylinder from its zero position, and means for returning said segment into its zero position independently of the movement of said cylinder, substantially as set forth.

5. In a machine of the character described for perforating jacquard cards for embroidering machines, the combination of a punching device comprising a plurality of feeler members, a rotatable perforated cylinder arranged to selectively control some of said feeler members and having a spiral thread on its periphery whereof the beginning and end are in line with the zero perforations of the cylinder, a rotatory perforated segment arranged to selectively control other of said feeler members and so constituted that the feeler members controlled thereby are inoperative on the punching device when the said cylinder does not rotate beyond its zero position, a feeler member arranged to coact with said spiral thread, a worm rotatable with, but slidable axially relatively to said cylinder, a lever carrying a detent operatively connected with said segment to rock the same, an axially slidable worm wheel meshing with said worm and having in one of its side faces notches for receiving said detent, a spring acting on said worm wheel and tending to hold the same in engagement with said detent, means operatively connecting said latter feeler member with said worm to shift the latter axially according to the amount of angular movement imparted to said cylinder from its zero position, and means for returning said segment into its zero position independently of the movement of said cylinder, substantially as set forth.

6. In a machine of the character described for perforating jacquard cards for embroidering machines, the combination of a punching device comprising a plurality of feeler members, a rotatable perforated cylinder arranged to selectively control some of said feeler members and having a spiral thread on its periphery whereof the beginning and end are in line with the zero perforations of the cylinder, a rotatory perforated segment arranged to selectively control other of said feeler members and so constituted

that the feeler members controlled thereby are inoperative on the punching device when the said cylinder does not rotate beyond zero position, a worm rotatable with 5 but slidable axially relatively to said cylinder, means comprising a feeler member arranged to coact with said spiral thread for moving said worm axially according to the amount of angular movement imparted to 10 said cylinder from its zero position, a three-armed lever positively operatively connected with said segment to rock the same, one arm of said lever having a detent directed parallel with the axis of the fulcrum 15 of the lever, an axially slidable worm wheel meshing with said worm and having in one of its side faces recesses for receiving said detent, a spring acting on said worm wheel and tending to hold the same in engagement 20 with said detent, and means comprising a periodically actuated yoke that is arranged to coact with the two other arms of said lever for returning the same and said segment into their normal positions, substantially as set forth.

7. In a machine of the character described for perforating jacquard cards for embroidery machines, the combination of a punching device comprising a plurality of feeler 25 members, a rotatable perforated cylinder arranged to selectively control some of said feeler members and having a spiral thread on its periphery whereof the beginning and end are in line with the zero perforations of 30 the cylinder, a rotatory perforated segment arranged to selectively control other of said feeler members and so constituted that the

feeler members controlled thereby are inoperative on the punching device when the said cylinder does not rotate beyond its 40 zero position, a feeler member arranged to coact with said spiral thread, a worm rotatable with but slidable axially relatively to said cylinder, means controlled by the latter feeler member for moving said worm axially according to the amount of angular movement imparted to said cylinder from its zero position, a sleeve having its axis disposed at right angles to the axis of said cylinder, segment and worm, a lever fast on said sleeve, links positively operatively connecting said lever to said segment, a three-armed lever fast on said sleeve and having on one arm thereof a detent directed parallel to the axis of said sleeve, a worm-wheel 50 that is slidable on said sleeve between said levers, meshes with said worm and has notches in its side face nearest said three-armed lever for receiving said detent, a spring interposed between the former lever 55 and said worm-wheel tending to hold the latter in engagement with said detent, a yoke arranged to coact with the two other arms of said three-armed lever for returning the same and said segment into their 60 normal positions, and means for actuating said yoke, substantially as set forth.

In testimony whereof I affix my signature in presence of two witnesses.

OTTO FAHRNI.
